ENGINE STARTER GEARING

James E. Buxton, Elmira, N. Y., assignor to Bendix Aviation Corporation, Elmira Heights, N. Y., a corporation of Delaware

Application June 2, 1950, Serial No. 165,819

4 Claims. (Cl. 74-7)

1

The present invention relates to engine starter gearing, and more particularly to that type of drive which engages an engine gear automatically when the starting motor is energized, and disengages when the engine starts.

It is an object of the present invention to provide a novel engine starter drive which is efficient and reliable in operation, small in size, and simple and economical in construction.

It is another object to provide such a device including an elastic connection which is arranged to slip when overloaded so as to protect the drive from excessive stresses.

It is another object to provide such a device in which the elastic connection is axially yieldable to assist in securing proper meshing of the gearing in case of tooth abutment between the drive pinion and engine gear.

Further objects and advantages will be apparent from the following description taken in connection with the accompanying drawing in which:

Fig. 1 is a side elevation partly broken away and in section of a preferred embodiment of the invention showing the parts in idle position; and

Fig. 2 is a similar view showing the parts in cranking position.

In Fig. 1 of the drawing there is illustrated a power shaft 1 on which a screw shaft 2 is fixedly mounted as by means of a cross pin 3 which is retained by a thimble 4 seated against a shoulder 5 on the screw shaft. A pinion 6 is slidably journaled on the power shaft for longitudinal movement into and out of mesh with a gear 7 of the engine to be started.

Means for actuating the pinion from the screw shaft is provided, comprising a control nut 8 threaded on the screw shaft and seated against a shoulder 9 formed at the termination of the threads of the screw shaft. A cylindrical member 11 having a radially inwardly directed flange 12 is fixedly connected to the pinion 6 as indicated at 13. The control nut 8 has a radial flange 14, and a spring member 15 is seated at one end on the control nut 8 against the flange 14, and at its other end within the cylindrical member 11 against the flange 12. The central convolutions of the spring 15 are normally spaced from each other as indicated at 16 so as to make the spring longitudinally compressible.

The dimensions of the parts are such that the spring engages the interior of the cylindrical member 11 and the exterior of the nut 8 with sufficient friction to transmit normal cranking loads.

2

The spring is so wound, as indicated, that when cranking torque is transmitted therethrough it tends to wind down to a smaller diameter, thus tending to relieve the frictional engagement between the spring and the cylindrical member 11 so that slippage takes place upon predetermined overload of the drive.

A barrel member 17 is arranged to surround the control nut and has its open end rigidly connected to the cylindrical member 11 in any suitable way, as shown at 18. The barrel member has a shoulder 19 which normally engages the flange 14 of the control nut and thus maintains the spring 15 under initial longitudinal compression between the flanges 14 and 12.

Barrel 17 has a terminal flange 21 resting on the power shaft 1 and positioned to engage the end of the screw shaft 2 when the drive is in cranking position. Preferably a thrust ring 22 is interposed to reduce wear and to define the meshed position of the pinion 6.

Means normally maintaining the drive in idle position is provided in the form of an anti-drift spring 23 located within the barrel, bearing at one end against the thrust ring 22 and at its other end seated on the thimble 4 against a flange 24 thereof.

Means for limiting the compression of spring 15 is provided in the form of a spacing ring or cylinder 25 located within the barrel 17 between the flange 14 of the control nut and a thrust ring 26 which bears against the end of the cylindrical member 11, so as to limit the travel of the control nut toward the pinion 6.

In operation, starting with the parts in the positions illustrated in Fig. 1, rotation of the power shaft 1 in the direction of the arrow (a) by the starting motor, not illustrated, causes the control nut 8 to be traversed to the right, which longitudinal movement is transmitted through the spring 15 to the cylindrical member 11, pinion 6 and barrel 17. Should the teeth of pinion 6 abut against the teeth of engine gear 7, the spring 15 is longitudinally compressed by the control nut 8 until sufficient torque is built up to index the pinion teeth into registry with the tooth spaces of the engine gear, whereupon the pinion is snapped into initial mesh with the engine gear by expansion of the spring 15, and the meshing movement of the pinion proceeds until the movement of the flange 21 is arrested by engagement of the thrust ring 22 against the end of screw shaft 2.

The movement of the control nut 8 is continued until the flange 14 engages the stop ring 25, at

which time the spring 15 is compressed firmly between the flanges 14 and 12, as shown in Fig. 2. Torque is then built up and transmitted through the spring 15 to rotate the pinion 6 and crank the engine. Should the initial torque due to the inertia of the parts exceed a predetermined overload, the spring 15 wraps down slightly, relieving its frictional connection with the interior of the cylindrical member 11, thus permitting slippage to take place until the excessive torque is dissipated; whereupon cranking proceeds normally without slippage.

When the engine starts, the acceleration of the pinion 6 by the engine gear 7 returns the parts to idle position with the assistance of the anti-drift spring 23, the backward movement of the control nut 8 being arrested by the shoulder 9 on the screw shaft. When this engagement takes place, the torque transmitted by the momentum of the overrunning parts tends to unwrap the spring 15 which permits the spring to slip on the control nut 8, and thus cushion the impact and prevent rebounding of the parts such as might cause undesired engagement of the pinion 6 with the engine gear 7.

Although but one embodiment of the invention has been shown and described in detail, it will be understood that various changes may be made in the precise design and arrangement of the parts without departing from the spirit of the invention.

I claim:

1. In an engine starter drive a power shaft, a screw shaft fixed thereon, a pinion slidably jour-

nalled on the power shaft for movement into and out of mesh with an engine gear, a cylinder fixed to the pinion, a control nut on the screw shaft, a coiled spring tightly engaging the periphery of the nut at one end, and at its other end frictionally engaging the interior of said cylinder, and a barrel member fixedly connected at one end to said cylinder and having a flange at its other end positioned to engage the end of the screw shaft when the pinion is in fully meshed position.

2. An engine starter drive as set forth in claim 1 in which the control nut and cylinder are provided with radial flanges engaging the ends of the spring, and the barrel is provided with a shoulder normally engaging the control nut flange and thus maintaining the spring under initial compression.

3. An engine starter drive as set forth in claim 2 in which the medial portion of the spring is provided with longitudinally spaced convolutions rendering the spring endwise compressible.

4. An engine starter drive as set forth in claim 3 including means for positively limiting the endwise compression of the spring.

JAMES E. BUXTON.
